DESIGN FOR A MILK BOTTLE HOLDER OR SIMILAR ARTICLE

Richard W. Dondlinger, Des Moines, Iowa

Application August 5, 1940, Serial No. 94,254

Term of patent 7 years

To all whom it may concern:

Be it known that I, Richard W. Dondlinger, a citizen of the United States and resident of Des Moines, Polk County, Iowa, have invented a new, original, and ornamental Design for a Milk Bottle Holder or Similar Article, of which the following is a specification, reference being had to the accompanying drawing, forming a part thereof.

Fig. 1 is a top plan view of a milk bottle holder or similar article, showing my design.

Fig. 2 is a front elevational view; and
Fig. 3 is an end elevational view thereof.

I claim:

The ornamental design for a milk bottle holder or similar article, substantially as shown.

RICHARD W. DONDLINGER.
